UNITED STATES PATENT OFFICE.

EMIL SCHNEIDER, OF MAILAND, ITALY.

ACCOUNTING MACHINE.

Application filed August 3, 1927, Serial No. 210,380, and in Germany August 5, 1926.

The present invention relates to a new and improved accounting machine and more particularly to a machine of the said type in which the leaf of books, sheets, etc. to be written upon are removably clamped on a flat holder or support.

In book-keeping certain words or combinations of words, numbers, or groups of numbers occur very frequently and the writing thereof occasions much loss of time.

The main object of the invention is to provide means which simplifies the work of the book keeper to obviate clerical errors.

I attain this and other objects by means of 15 a device which automatically prints words, numbers or certain groups of words and numbers on the sheets or leaves, the blocks stamps or types with the said words, etc., being always ready to be pressed upon the 20 sheets to obviate the composing of letter types and the loss of time connected therewith. The device may be constructed in such a manner that the duplicating or mani- 25 folding of the entry in the top sheet is possible to get with but one impression a number of copies.

The details of the invention are set forth in the following specification and claims and are illustrated in the annexed drawing in 30 a diagrammatical manner in which—

Fig. 1 is a sectional elevation of the machine,

Fig. 2 is a cross-section on line *a*—*b* of Fig. 1,

35 Figs. 3-6 show details of construction.

The machine shown comprises a table 1 having two guide-grooves 42, 42 running parallel to each other and in which a board 3 of a manifolding device is slidably ar- 40 ranged. The said manifolding device is known per se and comprises clips or clamps to hold the original entry sheet, the carbon paper and the copy sheet. On the said table 1 a support 2 having an arm extending over the said board 3, and below the table 1 and rigidly fixed thereto is an electric motor 5 of any known construction. The motor 5 drives by means of a worm 44 and a worm wheel 6 a vertical shaft 7 journaled in the support 2. On the upper end of said vertical shaft 7 a bevel gear 8 is loosely mounted which is in mesh with a bevel gear 33 fixed to a horizontal shaft 13 rotatably mounted in the horizontal extension of sup- 45 port 2. A disk 14 which is rigidly fastened to said shaft 13 carries a crank pin 45 which engages a vertical rod 34 slidably mounted in the head 46 of support 2. The rod 34 is provided with a collar 35 which supports a printing device 15. The device 15 com- 50 prises a casing 16 in which a shaft 24 is fixed. On the shaft 24 a number of disks 25 are arranged and on each disk 25 a ring 26 is rotatably mounted bearing on its outer circumference letters, numbers or signs which 55 are to be impressed. The rings 26 having angular cross-section are held by the heads of screws, 28, screwed into the disks 26. The inner circular face of each ring 26 is provided with notches 48, one for each letter, etc., on the outer circumference. In a radial bore of each disk 26 a pin 27 is ar- 60 ranged which stands under the action of a coiled spring 49 which keeps the pin 27 in engagement with one of the notches 48. By 65 applying sufficient stress on the ring 26 the resistance of the spring 27 may be overcome and the ring may be turned on the disk 26. The pin 27 however will retain the ring 26 in its position and secure it against acci- 70 dental displacement. To enable the disk to be turned more easily a handle 29 is fixed thereto. Over disks 25 a cover 30 of sheet metal is placed and fixed to the casing 16 and provided with a slot 50 for each disk 75 25 through which slots 50 the handles 29 project. The cover 30 is provided with letters, numbers, etc., corresponding to those attached to the rings 26. By adjusting the handle 29 opposite a number on the edge of 80 a slot 50 the said ring 26 is brought into such a position that the same letter is im- 85 pressed on the sheet by pressing the device 15 downwards. A type-writer ribbon 39 runs over guide rollers 40 and guide 90 pieces 51, the means to shift the ribbon are well known and are not shown in the drawings. Between a plate 36 screwed into the body portion of the device 15 and the collar 36 a spring 17 is arranged which 95 transmits the pressure from the rod 34 to the said body portion. Above the disks 25, 26 a dial plate 31 is fixed to the frame of the device and provided with devices, such as numbers, dates, weight amounts, order 100 numbers, etc., corresponding to those on the adjacent disks 26. The handles 29 may be made in different colors to facilitate the 105

working. The shaft 7 and the bevel gear 8 are connected by a friction clutch 12 of known construction which clutch may be thrown in and out of engagement by a foot 5 lever (not shown in the drawing). To said foot lever a rod 10 is attached; the upper end of the rod 10 is linked to one arm of a bell crank lever 11 pivotally mounted on a stud of the support 2. To the second arm 10 of said lever 11 a bolt 37 is linked which projects in the path of an arm 38 on one of the clutch members. By pressing on the foot lever the bolt 37 is drawn out of the path of arm 38 and the clutch transmits the 15 rotation of shaft 7 to the bevel gear 8 so that the crank 14, 45 reciprocates the rod 34. The disks 25, 26 are pressed on the sheet and an impression is made by means of the ribbon not only on the top sheet, but also 20 on the copy sheet. The foot lever when free returns the bolt 37 to its initial position and the gear 8 is arrested. To adjust the device to write on thin sheets or on the leaves of a book the crank pin 45 may be made 25 adjustable in radial direction on the disk 14. The spring 17 absorbs shocks. After each impression the board 3 is shifted exactly for one line to get the impression on consecutive lines of the sheet, etc. The board 3 is provided with a rack 22 with which a spur wheel 21 is in engagement. The wheel 21 is keyed to a shaft 53 journalled in bearings of the table 1. A set of bevel gears 20 connects shaft 53 with a vertical shaft 35 41 and a second pair of bevel gears 19 connects shaft 41 to a shaft 54 on which a ratchet wheel 18 is keyed. Arm 38 of clutch 12 forms a pawl cooperating with said wheel 18. On each turn of the crank disk 14 the 40 shafts 54, 41 and 53 make part of a full rotation sufficient to advance the board 3 with the sheet or leaf thereon for one line.

The book keeper in writing the bills on the original sheet uses the printing device as often as the words or phrases appear in 45 the entry to be made and he has only to add the additional words for changing each entry. A great saving of time is therefore obtained.

What I wish to secure by U. S. Letters 50 Patent is:—

1. In a machine of the class described, a table, a standard thereon having a horizontal arm, a vertical shaft revolvably mounted in said standard, a horizontal shaft revolvably 55 mounted in said arm having a crank at the outer end, gears connecting said shafts together, one of said gears being fixed to its shaft and the other being loose on its shaft, a clutch to lock the loose gear to its shaft 60 at will, means to rotate said vertical shaft, a board mounted slidably on said table and having a rack, a shaft geared to the vertical shaft and having a pinion engaging said rack, a vertically reciprocatory member 65 mounted in the horizontal arm and engaged by the pin of the crank, and a printing mechanism attached to and vertically movable by said vertically reciprocatory member.

2. A machine as claimed in claim 1 in 70 which the printing mechanism comprises a casing, a fixed shaft extending across the casing, a plurality of discs free to turn on said shaft, a printing ring revoluble on the periphery of each disc and having internal 75 ratchet teeth, each of said discs having spring pressed pawls to engage the teeth of the rings and secure them against casual rotation, and means to ink the printing characters on the outer periphery of said printing rings.

In witness whereof I affix my signature.

EMIL SCHNEIDER.
